UNITED STATES PATENT OFFICE.

FRANCIS KOENIG, OF PHILADELPHIA, PENNSYLVANIA, ASSIGNOR TO
REINHOLD G. LEDIG, OF SAME PLACE.

DESIGN FOR A TABLE.

SPECIFICATION forming part of Design No. 22,013, dated November 22, 1892.

Application filed October 19, 1892. Serial No. 449,398. Term of patent 3½ years.

To all whom it may concern:

Be it known that I, FRANCIS KOENIG, a subject of the Emperor of Germany, (having resided one year last past in the United States

5 and declared my intention of becoming a citizen thereof,) residing in the city and county of Philadelphia, State of Pennsylvania, have invented and produced a new and original Design for a Table, of which the following is a 10 specification, reference being had to the accompanying drawing, forming part thereof.

The leading features of my design for a table are the ornamental top-frame, the ornamental legs and the ornamental support for 15 the lower shelf.

In the drawing, A designates the top frame of the table, on the sides of which are ornaments B and at the corners thereof are scrolls C.

D designates the legs, which have widened

upper ends E, with scrolls F on the sides 20 thereof. Below the frame A and between the widened ends E of the legs are panels G of scrollwork.

H designates the lower shelf between the legs, the said shelf having around it the ornamental supporting-border J. On the legs D, adjacent to the border J, are scroll facings K.

L designates the feet of the table, the same being of scroll form. The top M is quadrilateral, and the shelf H is circular. 30

What I claim is—

The design for a table, substantially as shown and described.

FRANCIS KOENIG.
